UNITED STATES PATENT OFFICE.

JOSEPH N. BURNO, OF CHICAGO, ILLINOIS.

COIN-DEPOSIT RECEPACLE.

Application filed April 19, 1922. Serial No. 555,543.

To all whom it may concern:

Be it known that I, JOSEPH N. BURNO, a citizen of the United States, and resident of Chicago, county of Cook, State of Illinois, have invented certain new and useful Improvements in Coin-Deposit Receptacles, of which the following is a specification.

This invention relates to coin deposit receptacles, and has particular reference to 10 that class of apparatus adapted to be installed in restaurants and lunchrooms in which it is made a rule that the customer be required to deposit his coin or coins covering the proposed purchase before the 15 purchased article is delivered by the counter man.

An important object of the invention is 20 to provide in a device of the character mentioned, a means whereby previously inserted money may be easily observed subsequent to its being deposited, the money being so retained after deposited that the amount incident to each of the several purchases may be readily ascertained upon observing the 25 coin retaining means by which the money for the preceding purchase is held in view.

A further object of the invention is to 30 so construct the various elements that they may be easily assembled to produce a strong, durable device, which is inexpensive to manufacture and reliable in operation.

Other objects of the invention will become apparent from the following specification, taken in connection with the accompanying drawings in which;

Figure 1 is a front view of the device embodying my invention.

Figure 2 is a rear view of the device, the housing for the operating mechanism there- 40 of being broken away in order that certain operating elements enclosed thereby may be clearly shown.

Figure 3 is a central vertical section taken on line 3—3 of Figure 2, the housing for the 45 operating mechanism being removed.

Figure 4 is a transverse sectional view of the device taken on line 4—4 of Figure 3.

In the drawings wherein is shown what I at present consider the preferred form of 50 my invention, the numeral 5 indicates a coin box, having a removable drawer 6 arranged therein into which the coins are successively deposited as the machine is intermittently actuated. Upon the box 5 there is 55 imposed a bracket support 7, having a base 8, which is secured to the top of the box by

means of screws or the like 9. The support 7 is provided with a head or yoke 10, having arms 11, to which is journaled a shaft 12, carrying a ratchet wheel 13 suitably connected to the shaft 12 as by means of a set screw 14. The shaft 12 is prevented from longitudinal movement by means of a sleeve 15 interposed between the ratchet wheel 13 and one of the arms 11. 60

The shaft 12 terminates at its front end in a hub or disc 16, to which is attached a pair of glass or other transparent discs 17, the discs 17 being secured to the hub or disc 16 by means of screws 18 passed through 70 a face plate 19 and an intermediate disc 20, which is provided to maintain the transparent discs 17 in a spaced relation. 65

In order to encase the discs 17 at their peripheries there is provided a housing 21 comprising a pair of substantially circular bands 22 which are retained in position upon the box 5 by means of bolts or the like 23. These encircling bands are united by means of screws or the like 24, passed 75 through spacing washers 25, and serve to retain the two elements in the form of a rigid unit between which is arranged a coin guide 26 terminating at one end in a lip 27 arranged adjacent a coin slot 28 formed in the 80 top of the box 5 through which slot the several coins inserted through the coin receiving mouth 29 are adapted to enter the removable drawer 6. 85

The intermediate disc 20 is provided with 90 a plurality of radiating arms 30, which form a series of pockets 31 between the transparent disc, which pockets are adapted to be brought into registration with the coin mouth 29 and the slot 28 intermittently 95 through the operating mechanism 31' shown most clearly in Figure 2.

The operating mechanism includes an actuating lever 32 pivoted to an arm 33, carried by the support 7. The arm 33 is adapted to be retained normally in the position shown in Figure 2 by a spiral spring 34 which, at opposite ends is fitted over lugs 35 and 36 carried respectively by the actuating lever 32 and the arm or bracket 33. 100 It will be noted that the actuating arm 32 is limited in its movement under the influence of the spring 34 by a lug or finger 37 carried thereby, and adapted to engage the bracket 33, as clearly shown in Figure 2. 110 To the actuating lever 32, intermediate its ends, there is pivotally connected a pawl 38

which is adapted to intermittently engage the teeth 39 carried by the ratchet wheel 13. It is evident that as the actuating lever 32 is operated, the discs 17 are intermittently rotated, they being rotated upon each actuation of the lever 32 a sufficient distance to bring the pockets 31 successively into registration with the coin receiving mouth 29, and the slot 28. As the discs 17 are rotated, 10 the fingers 30, carried by the intermediate disc 20 are adapted to pass by a spring pressed pawl 40 mounted upon a pivot 41 intermediate the bands 22, the pawl 40 being retained normally in the position shown in 15 Figure 4 by means of a leaf spring 42. The pawl 40 is adapted to prevent the transparent discs 17 from rotating in a direction opposite to that caused by the operation of the actuating lever 32 thus insuring rotation 20 of the discs 17 always in a given direction.

In use when it is desired to make a purchase, money to the amount required is deposited into a pocket 31 registering with the coin receiving mouth 29 after which the 25 counter man delivers to the customer the purchased article and actuates the lever 32 causing the pocket into which the money has been deposited to advance through a predetermined arc to bring the next succeeding pocket into registration with the coin receiving mouth 29 ready to receive the money necessary to the next succeeding purchase. It will be noted that at all times the money incident to at least two purchases may be readily ascertained by observing the pockets containing the coins which have not as yet been deposited into the drawer 6 through the coin slot 28 as a result of the intermittent rotation of the disks 17.

Having thus described my invention, I claim:

1. A coin deposit receptacle comprising a coin box, having a coin passage formed therein, a pair of discs, spacing means for 45 said discs, divisional elements carried intermediate said discs forming a plurality of pockets, said pockets being adapted to receive coins, means for intermittently rotating said discs whereby said pockets are 50 brought into registration with the passage of said box.

2. A coin deposit receptacle comprising a coin box having a coin passage formed therein, a pair of transparent discs, means 55 for spacing said discs apart, divisional walls carried intermediate said discs, said walls forming a plurality of coin pockets intermediate said discs, a housing for said discs, said housing being provided with a coin mouth, means for intermittently rotating 60 said discs whereby said pockets are brought into registration with said coin passage and said coin mouth.

3. A coin deposit receptacle comprising 65 a coin box having a coin passage formed

therein, a pair of transparent discs, means for spacing said discs apart, divisional walls carried intermediate said discs, said walls forming a plurality of coin pockets intermediate said discs, a housing for said discs, 70 said housing being provided with a coin mouth, means for intermittently rotating said discs whereby said pockets are brought into registration with said coin passage and said coin mouth, and means for locking said discs against rotation in a reverse direction. 75

4. A coin deposit receptacle comprising a coin box having a coin passage formed therein, a pair of transparent discs, means for spacing said discs apart, divisional walls 80 carried intermediate said discs, said walls forming a plurality of coin pockets intermediate said discs, a housing for said discs, said housing being provided with a coin mouth, means for intermittently rotating said discs whereby said pockets are brought into registration with said coin passage and said coin mouth, and means for locking said discs against rotation in a reverse direction including a spring pressed pawl adapted to successively engage said walls when said discs are rotated and brought into successive registration with said coin mouth and passage. 85

5. A coin deposit receptacle comprising a coin box having a coin passage formed therein, a pair of transparent discs, a hub disposed intermediate said discs, a plurality of divisional walls radiating from said hub forming a plurality of pockets around said hub and between said discs, a casing encircling said discs, means for intermittently rotating said discs whereby said pockets are successively brought into registration with said coin mouth and coin slot, a coin guide 105 arranged within said casing for retaining coins within said pockets until such time as they are brought into registration with said coin passage. 110

6. A coin deposit receptacle comprising a coin box having a coin passage, a shaft, a pair of transparent discs carried by said shaft, a spacing member intermediate said discs, a plurality of divisional walls intermediate said discs, said walls forming a plurality of coin pockets, an actuating lever associated with said shaft for rotating said discs intermittently whereby said pockets are brought successively into registration with said coin mouth and said coin passage. 115

7. A coin deposit receptacle comprising a coin box having a coin passage, a shaft, a pair of transparent discs carried by said shaft, a spacing member intermediate said discs, a plurality of divisional walls intermediate said discs, said walls forming a plurality of coin pockets, an actuating lever associated with said shaft for rotating said discs intermittently whereby said pockets are brought successively into registration with 120 125 130

said coin mouth and said coin passage, and means for retaining coins within said pockets until such time as said pockets are brought into registration with said coin passage.

5 8. A coin deposit receptacle comprising a coin box having a coin passage, a bracket carried by said coin box, a shaft journaled to said bracket, a pair of discs carried by said shaft, a plurality of divisional walls intermediate said discs forming a plurality of pockets adapted to receive coins, a ratchet wheel connected to said shaft, an actuating lever pivotally connected to said bracket, said actuating lever being adapted to cooperate with said shaft to intermittently rotate said discs whereby said pockets are brought successively into registration with said coin passage.

9. A coin deposit receptacle comprising a coin box having a coin passage, a bracket carried by said coin box, a shaft journaled to said bracket, a pair of discs carried by said shaft, a plurality of divisional walls intermediate said discs forming a plurality of pockets adapted to receive coins, a ratchet wheel connected to said shaft, an actuating lever pivotally connected to said bracket, said actuating lever being adapted to cooperate with said shaft to intermittently rotate said discs whereby said pockets are brought successively into registration with

said coin passage, a casing enclosing the periphery of said discs, and means disposed within said casing for retaining the coins within said pockets until such time as they are brought into registration with said coin passage.

10. A coin deposit receptacle comprising a coin box having a coin passage, a bracket carried by said coin box, a shaft journaled to said bracket, a pair of discs carried by said shaft, a plurality of divisional walls intermediate said discs forming a plurality of pockets adapted to receive coins, a ratchet wheel connected to said shaft, an actuating lever pivotally connected to said bracket, said actuating lever being adapted to cooperate with said shaft to intermittently rotate said discs whereby said pockets are brought successively into registration with said coin passage, a casing enclosing the periphery of said discs, means disposed within said casing for retaining the coins within said pockets until such time as they are brought into registration with said coin passage, means for locking said discs against rotation in a reverse direction, and means for returning said actuating lever to its normal position.

In testimony whereof, I have affixed my signature to this specification.

JOSEPH N. BURNO.
